UNITED STATES PATENT OFFICE.

CLARK F. RIGBY, OF BUTLER, PENNSYLVANIA.

CLUTCH AND CLUTCH-ACTUATING MEANS.

1,142,120.

Specification of Letters Patent.

Patented June 8, 1915.

Application filed May 14, 1913. Serial No. 767,606.

To all whom it may concern:

Be it known that I, CLARK F. RIGBY, a citizen of the United States, and resident of Butler, in the county of Butler and State of Pennsylvania, have invented certain new and useful Improvements in Clutches and Clutch-Actuating Means, of which the following is a specification.

The use of wire cable for deep well drilling presents conditions that are not encountered with manila cable, the same being due mainly to the absence of elasticity in the wire. The elasticity of "stretch" of manila cable prevents sudden shock or jar to the actuating mechanism when lifting the tools on their up stroke. But with wire cable there is no compensation, and the weight of the tools, which frequently amounts to several thousand pounds, is suddenly thrown on the 20 constantly running mechanism on each up stroke. Expedients have been proposed heretofore for providing the requisite compensation, among them the mechanism of my Patent No. 798,449, August 29, 1905. 25 But the latter has not proven entirely effective because of the sudden connection between the relatively movable parts and also because of the rebound in the cushioning mechanism. These difficulties are overcome 30 by the present invention which provides a combined braking and clutching action which is automatically released during the down stroke of the tools when the movement of the shaft exceeds the band wheel 35 and which is automatically set when the band wheel overtakes the shaft, this after the tools have completed their down stroke. At this instant there is an appreciable pause in the movement of the shaft followed by a 40 gradual clutching of the band wheel thereto as distinguished from a sudden or abrupt connection. Hence, the load is picked up gradually or with such a compensating action as to avoid injurious shock. The combined brake and clutch mechanism is of 45 double acting form and is set with the same effect when the movement of the band wheel exceeds the movement of the shaft as when the motion of the shaft exceeds the band 50 wheel, with provision for so adjusting the parts that the free relative movements of the band wheel and shaft may be of longer or shorter duration as desired.

A further object of the invention is to so 55 arrange the connections between the tool operating mechanism and band wheel that the

latter may rotate at a substantially uniform speed and hence be driven by an explosive engine. This result has not been possible heretofore in deep drilling operations because the enormous weight of the tools and cable has always operated to accelerate the movement of the band wheel on the down stroke and correspondingly lower its speed on the up stroke, thereby causing unavoidable fluctuations in the speed of the motor. 60 This is one reason why steam engines have been almost universally used heretofore for deep drilling as they readily respond to the fluctuations referred to. Indeed, one of the 65 most noticeable features of a deep drilling operation is the intermittent action of the steam engine which speeds up on each down stroke of the tools and slows down on the up stroke. Sudden variations of this kind are 70 not possible with explosive engines because their speed is relatively constant due to the heavy fly wheels with which they are necessarily equipped and which obviously preclude sudden and momentary increase and 75 decrease in speed. In the apparatus of the present invention the relatively fast and slow movements of the crank shaft are taken care of in such manner by the mechanism which connects the shaft and band wheel that 80 the speed of the latter is substantially unchanging and hence is peculiarly well adapted to be driven by an explosive engine.

In the accompanying drawings, Figure 1 is a side elevation of drilling apparatus embodying the invention, the parts being shown in position with the beam actuating pitman and crank on the down stroke as when lifting the tools within the well. In Fig. 2 the full line position of the parts shows them 90 immediately after completing the lifting stroke and when the shaft has been released from the band wheel by the accelerated down stroke of the tools, and in dotted lines the parts are shown in position to again clutch 95 together the band wheel and crank shaft, the accelerated movement of the crank shaft causing the clutch mechanism movable with it to overtake a clutch actuating stop carried by the band wheel. Fig. 3 shows the 100 position of the crank at the completion of the down stroke of the tools and the movement of the band wheel relatively to the crank during the momentary pause in the movement of the crank. Fig. 4 is a vertical section of the band wheel, crank shaft and combined brake and clutch mechanism. Fig. 5

is a section of the brake and clutch mechanism, taken on line 5—5 of Fig. 4. Fig. 6 is a sectional detail on line 6—6 of Fig. 5. Fig. 7 is a detail of the crab clutch for permanently connecting the band wheel and crank shaft. Fig. 8 is a top plan, partly in section, of the apparatus illustrated in Fig. 1. Fig. 9 is a detail of one of the adjustable clutch actuating stops carried by the band wheel, and Fig. 10 is a cross section on line 10—10 of Fig. 9.

Referring to the drawings, the entire apparatus is preferably mounted on sills 2 from which rise the samson post 3 and jack 15 posts 4, and which also support bed 5 of the explosive engine 6. Journalized on posts 4 is shaft 7 carrying crank 8 to which is connected pitman 9 for actuating the walking beam 10, the wire drilling cable 11 being 20 connected to the latter by the usual temper screw mechanism. Keyed to shaft 7 is sleeve 12 which carries the brake and clutch operating arm 13, presently to be described. Rotatable on sleeves 12 is band wheel 14, 25 and secured to one side thereof is the annular brake and clutch head 15 having its periphery formed with the wedge-shaped groove 16. Head 15 is adapted to be embraced by the semi-circular shoes 17 and 18 30 which at one side are adjustably connected together by bolt 19 confined in suitable lugs on the shoes. The connection with the bolt is such that the shoes are independently movable, and interposed between the shoe 35 extremities is coiled spring 20 which operates to hold the shoes normally expanded, as will presently appear. Carried by the shoes are the oppositely disposed arms 21 which are connected to the clutch operating 40 mechanism.

Arm 13 of the shaft-embracing sleeve 12 is provided with the opposite bifurcated arms 22 to which the shoe arms 21 are connected by pivot bolts 23, the latter being 45 capable of limited independent movement in the enlarged pivot confining openings 24 of arms 21. Fulcrumed between its ends at 25 to the extremity of arm 13 is lever 26, and connected to pin 27 carried by the inner end 50 of this lever are slotted links 28 and 29, the former connected to pivot 23 of shoe 17 while link 29 is similarly connected to the pivot of shoe 18.

The operation of the brake and clutch is 55 as follows: With lever 26 in central position, as in Figs. 5 and 6, neither clutch shoe is under tension and spring 20 holds the shoes separated or in open position. But upon turning lever 26 on its fulcrum the shoes 60 are necessarily caused to clutch head 15. If the outer end of lever 26, Fig. 5, is moved to the left tension is exerted on link 28 and shoe 17, at such time pin 27 moving in the slot of link 29, and the stress thus placed on 65 shoe 17 causes pivot 23 of shoe 18 to move

to the outer end of its confining opening 24, and with the free portion of shoe 18 thus held both clutch shoes are caused to tightly grip head 15. Exactly the same result follows the movement of lever 26 in the opposite direction, at such time link 29 and shoe 18 transmitting the clutch setting force. For operating lever 26, the free outer portion thereof is extended between the two oppositely facing cushion stops 30 and 31 70 adjustably secured to band wheel 14. Each of these stops, shown in detail in Figs. 9 and 10, is movable in a tubular casing 32, being held normally projected by spring 33. A perforated clip 34 at the rear end of casing 32 is adjustably fastened to curved bracket 35 secured to the band wheel, the latter being of channel form and slotted longitudinally at 36 to receive the clamping bolt 37 with nut 38 confined in the channel. Thus by slackening the clamping bolts the 75 stops may be adjusted as desired for determining the independent movement of the clutch and band wheel, also for determining the relative positions of said parts when operating the clutch. The down stroke of crank 8, pitman 9, and the rear end of beam 10 operates to raise the tools in the well after a blow has been struck, the band wheel having been moved to engage stop 30 with lever 26, as in dotted lines in Fig. 3, thereby oscillating the latter and clutching the crank shaft to the band wheel in the manner above described, and this relation of the parts continues until the tools have been 80 fully raised and crank 8 moved over the bottom center. At this juncture the tools begin to lower and the enormous weight thereof so accelerates the movement of the crank shaft as to rotate it more rapidly than the 85 band wheel with the result that lever 26 is moved out of contact with stop 30, as in full lines in Fig. 2, and the clutch mechanism assumes the normal released position shown in 90 Fig. 5. This accelerated movement of the 95 crank shaft causes lever 26 to approach stop 31, but as the latter is advancing in the same direction though at slower speed it is not overtaken by the lever until almost the instant the tools strike the bottom of the hole 100 when the parts are in the dotted line position shown in Fig. 2. Hence, by the time stop 31 is engaged and lever 26 operated to set 105 the clutch the tools have nearly or altogether finished their drilling stroke, and the 110 pull caused by the weight of the cable plus the momentum of the crank shaft marks the force that is cushioned by the ensuing clutching action. But this force is absorbed 115 so gradually by the brake-like clutch, especially in view of the fact, that the crank and band wheel are moving in the same direction, that no undue shock results and there 120 is no disturbing accelerated pull exerted on the engine. The checking of the movement 125 130

at the completion of the effective stroke of the tools and before completion of the full down stroke of the cable prevents violent twisting and kinking of the latter within 5 the well due to the slack. The described 10 operation results in the crank shaft coming to an appreciable stop immediately after passing a top center position, this without rebounding or reaction of any kind, and this 15 pause continues until lever 26 is overtaken by stop 30 on the band wheel whereupon the gradual or brake-like clutching action is again brought into play and the band wheel gradually takes on the load of the tools for 20 their upstroke without sudden jerk or injurious shock.

The gearing between the engine and band wheel should be of such form as to prevent slipping not only when the mechanism is 25 doing its heaviest duty, as when lifting the tools, but also when the parts are clutched together during the completion of the down stroke of the cable after the tools have struck the bottom. The preferred form of 30 gearing consists of a wire rope belt 40 which is wound twice around band wheel 14, the latter formed with two parallel grooves 41 and the belt passing around the slack-adjusting sheave 42 for directing it from one 35 groove to the other. Sheave 42 is secured to pivoted post 43 provided with the turnbuckle stay or brace 44. The two strands of the belt embrace sheaves 45 which are loose on crank shaft 46 of the explosive engine 6. Each sheave 45 carries a clutch disk 47, and the latter are adapted to engage the combined clutch heads and fly-wheels 48 on the engine shaft. The clutch disks and the sheaves carried thereby are moved into 40 clutching position by wedges 49 connected by links to a lever 50 which is fulcrumed between its ends to the engine frame and which is operated to throw either one clutch or the other by rod 51 connected to hand lever 52. The belt is passed from one sheave 45 to the other sheave of like number around the slack-adjusting idler 53 supported by the engine frame and movable toward 45 and from the engine crank shaft by screw 54. The double winding of the driving belt precludes slipping, and furthermore, enables me to form the belt of wire cable which is a distinct advantage in well drilling practice over flat band belts of usual form. A band 55 wheel for well drilling apparatus of the type specified is new in the art and provides for positively communicating the motion of the engine at all times without slipping under momentary and sudden variations in 60 the load as well as variations between the speed of the band wheel and crank shaft. And with a wire cable belt geared to an explosive engine as herein shown, the direction of rotation of the band wheel may be reversed 65 without interfering with the normal

operation of the engine. The band wheel may be permanently clutched to the crank shaft by a crab 58, Figs. 4 and 7, when a positive drive is required for actuating the bull wheels and other auxiliary mechanisms, 70 not shown, the power for such purposes being transmitted from the band wheel 14 by a supplemental band wheel 59 secured thereto.

I claim:

1. In well drilling apparatus, the combination of a shaft adapted to operate drilling tools, an actuating wheel for the shaft with the shaft and wheel adapted to rotate independently of each other, a clutch for connecting the wheel and shaft, and means actuated by independent movement of either the shaft or wheel for setting the clutch. 75

2. In well drilling apparatus, the combination of a shaft adapted to operate drilling tools, an actuating wheel for the shaft with the shaft and wheel having limited rotary movement independently of each other, a clutch for connecting the wheel and shaft, a clutch setting device movable with said shaft, and means carried by the wheel for actuating the setting device when either the shaft or the wheel has reached the limit of its independent movement. 85

3. In well drilling apparatus, the combination of a shaft adapted to operate drilling tools, an actuating wheel for the shaft with the shaft and wheel having limited rotary movement independently of each other, a clutch for connecting the wheel and shaft, a clutch setting device movable with the shaft and having independent movement in opposite directions and adapted when moved in either direction to set the clutch, and means carried by the wheel and adapted to independently move the clutch setting device when either the shaft or wheel has reached the limit of its independent movement. 95

4. In well drilling apparatus, the combination of a shaft adapted to operate drilling tools, an actuating wheel for the shaft with the shaft and wheel having limited rotary movement independently of each other, an arm projecting from the shaft, a clutch for connecting the wheel and shaft, a clutch setting device pivoted to the arm and operatively connected to the clutch for setting the latter when moved in either direction on its pivot, and devices spaced apart on the wheel in the path of the clutch setting device with one of said devices adapted to engage and actuate the clutch setting device when either the shaft or the wheel has reached the limit of its independent movement. 110

5. In well drilling apparatus, the combination of a shaft adapted to actuate drilling tools, an actuating wheel for the shaft with the shaft and wheel having limited rotary movement independently of each other, an 120

125

130

- annular head carried by the wheel, an expandible clutch adapted when set to grip the said head, a support movable with the shaft, a clutch setting device fulcrumed to the support and operatively connected to opposite portions of the clutch and adapted to set the latter when moved in either direction on its fulcrum, and devices spaced apart on the wheel in the path of the clutch setting device and adapted to actuate the latter when either the shaft or the wheel has reached the limit of its independent movement.
6. The combination of a shaft and a shaft actuating wheel each having limited independent rotary movement, a wheel engaging clutch having separated extremities adapted to be contracted for setting the clutch and expanded for opening the same, a clutch support carried by the shaft with the separated extremities of the clutch connected to and having limited independent movement relatively to the support, a clutch setting device fulcrumed to the support and pivotally connected to the clutch extremities, and separated devices movable with the wheel in the path of the clutch device with one or the other of the wheel carried devices adapted to oscillate the clutch setting device when either the shaft or the wheel has reached the limit of its independent movement.
7. The combination of a shaft and a shaft actuating wheel each having limited independent rotary movement, a wheel engaging clutch having separated extremities adapted to be contracted for setting the clutch and moved apart for opening the same, a support movable with the shaft, means movably connecting the opposite extremities of the clutch to the support, a clutch setting device fulcrumed to the support, links extending from the extremities of the clutch and each having a pin and slot connection with the setting device whereby the clutch is adapted to be set when either extremity thereof is drawn upon by the clutch setting device, and devices carried by the wheel in the path of the clutch setting device with one or the other of the wheel-carried devices adapted to actuate the setting device when either the wheel or shaft has reached the limit of its independent movement.
8. The combination of a shaft and a shaft actuating wheel having independent rotary movement, a support movable with the shaft and formed with two slots separated in the direction of the circumference of the wheel, a wheel engaging clutch adapted to contract when set with pins at the separated extremities of the clutch entered in the support slots, a clutch setting device fulcrumed to the support, links extending from the clutch extremities to said device and having pin and slot connections therewith whereby movement of the clutch setting device in

either direction on its fulcrum causes it to pull on one extremity of the clutch while the other extremity of the latter is held to the support, and separated devices in the path of and adapted to engage the clutch setting device when either the shaft or the wheel has reached the limit of its independent movement. 70

9. The combination of a shaft and a shaft actuating wheel rotatable independently of each other, a support movable with the shaft, a clutch engaged head carried by the wheel a band-like clutch having its extremities movably connected to the support with the extremities adapted to move toward each other and with the support restricting movement of the clutch parts away from each other, a clutch setting device fulcrumed to the support, connections between the extremities of the clutch and the setting device 80 whereby the latter may be caused to draw upon either clutch extremity, and separated devices carried by the wheel in the path of the clutch-setting device and adapted to engage and oscillate the latter for setting the 90 clutch when either the shaft or the wheel reaches the limit of its independent movement. 85

10. The combination of a shaft and a shaft-actuating wheel rotatable independently of each other, a clutch rotatable with the shaft for uniting the shaft and wheel, a clutch actuator movable with the clutch, stop devices on the wheel at opposite sides of the actuator and in the path thereof and adapted to engage the latter for operating the clutch, and means for adjusting the stop devices toward and from each other. 95

11. The combination of a shaft and a shaft actuating wheel rotatable independently of each other, a clutch rotatable with the shaft for uniting the shaft and wheel, a clutch actuator movable with the clutch, stop devices on the wheel at opposite sides of and in the path of the actuator and adapted to be engaged by the latter for operating the clutch, each stop device consisting of a socket, a plunger-like head projecting from the socket, and a spring within the socket and opposing inward movement of the head. 105 110

12. The combination of a shaft and a shaft actuating wheel rotatable independently of each other, a clutch rotatable with the shaft for uniting the shaft and wheel, a clutch actuator movable with the clutch, slotted supports on the wheel at opposite sides of the actuator, and reversely arranged stop devices adjustable on the supports and adapted to be engaged by the actuator for operating the clutch. 115 120

13. The combination of a shaft and a shaft actuating wheel, a clutch head rotatable with the wheel, a clutch carrier movable with the shaft, a head engaging clutch of band form having separated free extremi- 130

ties movably secured to the carrier, the clutch formed in two pivotally connected parts, a spring operating to hold the two-part clutch normally open, lever mechanism 5 for contracting the clutch parts into engagement with the clutch head, and means carried by the wheel for operating the lever mechanism.

14. The combination of a shaft and a 10 shaft actuating wheel, a clutch head rotatable with the wheel, a clutch carrier movable with the shaft, a head engaging clutch having separated extremities movably secured to the carrier, the clutch formed in 15 two parts, means pivotally and adjustably connecting the parts, a spring for opposing contraction of said parts into clutching position, mechanism operatively connected to

the clutch parts for contracting the same into engagement with said head, and means 20 carried by the wheel for operating said mechanism.

15. In well drilling apparatus, the combination of a shaft for operating drilling tools, a constant speed driving wheel for the shaft, 25 and means actuated by independent relative movement of the said shaft or of said wheel for causing said shaft and wheel to move in unison.

In testimony whereof I affix my signature 30 in presence of two witnesses.
